DESIGN FOR A COMBINED LAMP BASE AND STANDARD OR SIMILAR ARTICLE

Jerome H. Steinberg, Brooklyn, N. Y.

Application June 7, 1945, Serial No. 119,945

Term of patent 3½ years

(CL. D48—20)

To all whom it may concern:

Be it known that I, Jerome H. Steinberg, a citizen of the United States, residing at Brooklyn, in the county of Kings and State of New York, have invented a new, original, and ornamental Design for a Combined Lamp Base and Standard or Similar Article, of which the following is a specification, reference being had to the accompanying drawing, forming part thereof.

In the drawing:

Fig. 1 is a front view of a combined lamp base and standard, showing my new design; and

Fig. 2 is a side view thereof.

I claim:

The ornamental design for a combined lamp base and standard or similar article, substantially as shown.

JEROME H. STEINBERG.
